THERMALLY OPERATED BI-METALLIC
ELECTRIC DEVICES

Philip Woodhall, Manchester, and Kenneth Hale, Eccles, England, assignors to The General Electric Company Limited, London, England

Filed Dec. 18, 1959, Ser. No. 860,473
10 Claims. (Cl. 200—138)

This invention relates to thermally operated bi-metallic electric devices, such as cut out switches, and more particularly, but not exclusively, to devices used as protective means in electrical equipment such as electric kettles.

According to the present invention a thermally operated bi-metallic device, comprises a bi-metallic element, a slave disc mounted adjacent to the element, means to transmit motion or force from the bi-metallic element to the slave disc, the slave disc being so arranged as to resist the motion of force transmitted from the bi-metallic element, and electric contact means including a pair of concentrically arranged contacts in a unitary assembly, the outer of the terminal contacts engaging the periphery of the slave disc and the inner terminal contact being adapted to make and break contact with a central contact portion of the slave disc.

Means may be provided for adjusting and setting the temperature at which the bi-metallic element operates, and the means may comprise an internally threaded portion surrounding the threaded periphery of the outer of the two concentrically arranged terminal contacts, in which portion the terminal assembly may be rotated to give simultaneous longitudinal adjustment of the terminal contacts.

The thermally operated bi-metallic device may be provided with manually operable reset means which may comprise a sleeve arranged to be slid over the outside of the device and to engage with a projection, or a plurality of projections, from the bi-metallic element.

In order that the invention may be clearly understood one construction of an electric cut out switch for use in a domestic electric kettle will now be described by way of example with reference to FIGURE 1 of the accompanying drawings which shows a front sectional elevation of the switch, a modification of this construction will also be described, and is shown partly in section in FIGURE 2 of the drawings. The device is arranged to fit in a suitable pocket in the head of the immersion heater of the kettle.

Referring now to FIGURE 1, the switch is contained in a switch body comprising a spun copper can 1 which holds two porcelain ceramic body members 2, 3 together. The can 1 has a hole 4 in the end face 5 thereof and this hole 4 is covered by a bi-metallic element 6 in the form of a disc situated in a recess 7 in the body member 2 behind the end face of the can 1. The body member 2 is centrally apertured and a push rod 8 is placed in the aperture and arranged in such a manner that it is free to move in a direction perpendicular to the end face 5 of the can 1. One end of this push rod 8 rests upon the bi-metallic element 6 and its movement is a slave movement dependent upon the movement of the bi-metallic element.

The other end of the push rod 8, i.e. the end remote from the end face 5, is in contact with a spring slave disc 9 made of Phosphor bronze or a similar spring resilient electrically conducting material, and the disc 9 is situated in a cavity in the centre of the switch formed by the member 2 spanning a recess 10 in the member 3. The disc has at its center on the side remote from the push rod 8 an electrical contact 11, and on the side adjacent to the push rod there is a small projection 12 which is arranged to fit into a recess in the end of the

2

push rod 8 and thereby positively locate the slave disc 9 with respect to the push rod 8.

The terminal contact assembly of the switch comprises a unitary assembly of substantially T form with the top portion of the T positioned in the recess 10 and the shank portion of the T passing through a centrally arranged aperture in the body member 3. The terminal contact assembly consists of an inner terminal contact 13 threaded at its outer-most end 14 and with its contact end 15 situated in line with contact 16. The terminal contact 13 is surrounded by a concentrically arranged outer terminal contact 16 threaded on its outer surface 17. The two terminal contacts are separated by a pair of ceramic insulating bushes 18, 19, and these bushes and indeed the whole terminal contact assembly are held together by means of a lock nut 20 screwed on the threaded portion 14 of the terminal contact 13.

The terminal contact assembly is screwed into an internally threaded portion of the switch body in the form of a ring 21 set in the body member 3 so that the ends 15, 22 of the contacts 13, are disposed in the recess 10. The whole assembly 5 is then secured in place in the member 3 by means of a lock nut 23 on the threaded portion 17 of the terminal contact 16.

In operation the end face 5 of the switch is placed adjacent to a portion of the kettle heating element and under normal conditions the bi-metallic element 6 is in the position shown where it urges the contact 11 on the slave disc 9 into engagement with the terminal end 15 of the terminal contact 13, and thereby completing an electric circuit from the terminal 13 through the slave disc 9 to the contact end 22 of the terminal contact 16. The edges of the slave disc 9 rest on the contact end 22, the slave disc is under tension due to the force exerted thereupon by the bi-metallic element 6.

When the kettle heating element reaches a temperature higher than normal the bi-metallic element 6 snaps over in a direction towards the kettle element and since its force on the slave disc 9 is released and due to the resilient nature of this slave disc, the disc assumes its more natural untensioned position and the contact 11 separates from the contact end 15 thereby breaking the electrical circuit.

To set the switch to operate at the correct temperature the end face 5 is placed flat on a metal plate which is at the correct temperature and the bi-metallic element 6 is allowed to soak in the heat until it attains that temperature. Then, with the lock-nut 23 free, the terminal assembly can be screwed in the ring 21 in the direction of the end-face 5 until the pressure exerted on the bi-metallic element 6 through the push rod 8 and the slave disc 9 is sufficient to snap-over the bi-metallic element 6. The lock nut 23 is then tightened up and the switch is set to operate at the temperature of the soak plate.

The slave disc 9 may be in the form of a bevelled washer, and the set of the disc may be such that when the contacts are open not only does the central contact 11 on the terminal 13 separate from the end contact 15 but the edges of the slave disc 9 may rest upon the bush 19.

Referring now to FIGURE 2, here a manually operable reset device is incorporated and the bi-metallic disc 6 is provided with two radially projecting ears 25, one on either side of the disc, which project through holes 26 in the ceramic body member 2 and the copper can 1. The end of the copper can 1 at the end face 5 is modified slightly from the device described with reference to FIGURE 1 inasmuch as the edges of the can at the hole 4 are turned inwardly to provide a flange 27 upon which the disc 6 rests, and which provides a pivot point for the disc when it changes over from one position to another.

A sleeve 28 is provided around the outside of the can

1, and this sleeve has a coiled compression spring 29 surrounding it and located between the ears 25 of the disc 6 and a flange member 30 attached to the top of the sleeve 28. The purpose of the spring 29 is to spring load the sleeve 28 and to keep it clear of the disc 6 during normal conditions.

In the position shown the bi-metallic switch has operated and has changed over to open the switch, the reset temperature of the disc is set below the normal ambient so that for the switch to reclose itself the temperature of the disc will have to be lowered considerably below that of normal operating conditions. If this is not possible and when the ambient has cooled below the temperature at which the contacts opened pressure can be exerted in a downwards direction on the flange 30, forcing the ends of the sleeve 28 against the ears 25 and overcoming the force of the spring 29. Further forcing downwards of the flange 30 urges the ears 25 downwards and when they are depressed below the centre line of the disc 6 the disc changes over and closes the contacts of the switch. Pressure is then released from the flange 30 and the spring 29 returns the sleeve 28 to a natural position resting on the uncompressed spring 29.

It will be appreciated that by incorporating a manual reset device the utility of the switch is increased, since the kettle can be refilled with water after operation of the switch, even though the temperature of the water may be higher than the reset temperature of the disc 6, whereas without such a device the kettle could not be used again until the temperature of the water had fallen below the reset temperature.

Should the device be reset manually while the temperature of the disc is still above the operating temperature the switch will re-open again immediately pressure is released from the ears, and it does not therefore impair the safety of a switch to incorporate such a reset device.

We claim:

1. A thermally operated bi-metallic device comprising a bi-metallic element, a slave disc mounted adjacent to the element, said slave disc having a peripheral contact portion and a central contact portion, means to transmit motion or force from the bi-metallic element to the slave disc, the slave disc being so arranged as to resist the motion or force transmitted from the bi-metallic element, and electric contact means including a pair of concentrically arranged terminal contacts in a unitary assembly, said terminal contacts being electrically insulated from one another, the outer of the terminal contacts engaging the peripheral contact portion of the slave disc and the inner terminal contact being adapted to make and break contact with the said central contact portion of the slave disc.

2. A thermally operated bi-metallic device as claimed in claim 1, wherein means are provided for adjusting and setting the temperature at which the bi-metallic element operates.

3. A thermally operated bi-metallic device as claimed in claim 2, wherein the adjusting means for adjusting and setting the temperature at which the bi-metallic element operates comprises an internally threaded portion surrounding the outer of the two concentrically arranged terminal contacts and disposed in screw-threaded engagement therewith, in which portion the terminal assembly is rotatably arranged to give simultaneous longitudinal adjustment of the terminal contacts, and means for locking the terminal assembly in an adjusted position.

4. A thermally operated bi-metallic device as claimed in claim 1, wherein the device is provided with manually operable reset means.

5. A thermally operated bi-metallic device as claimed in claim 4, wherein the reset means comprises a sleeve slidably arranged over the outside of the device, said bi-metallic element having peripheral projections arranged to be engaged by said sleeve.

6. A thermally operated switching device comprising

a switch body, a pair of terminal contacts carried by said body, said contacts being concentrically arranged and electrically insulated from one another, a movable contact member adapted to bridge said contacts, said movable contact member comprising a flexible disc having a peripheral contact portion engaging the outer of said terminal contacts and a central contact portion adapted to make and break contact with the inner of said terminal contacts, a bi-metallic element mounted adjacent to said disc, and means for transmitting a force from the bi-metallic element to the disc for urging said central contact portion of the disc into engagement with the inner of said terminal contacts, said disc being resiliently biased to resist the force transmitted from the bi-metallic element.

7. A thermally operated switching device comprising a switch body, a terminal contact assembly carried by said body, said assembly comprising inner and outer terminal contact members concentrically arranged and electrically insulated from one another, means for adjusting the position of said terminal contact assembly within said body, means for locking said terminal contact assembly in an adjusted position, a movable contact member adapted to bridge said terminal contact members, said movable contact member comprising a flexible disc having a peripheral contact portion engaging the said outer terminal contact member and a central contact portion adapted to make and break contact with the said inner terminal contact member, a bi-metallic element mounted adjacent to said disc, and means for transmitting a force from the bi-metallic element to the disc, for urging said central contact portion of the disc into engagement with said inner terminal contact, said disc being resiliently biased in accordance with the adjustment of said terminal contact assembly to resist the force transmitted from the bi-metallic element.

8. A thermally operated switching device comprising a switch body, said switch body providing an internally threaded portion, a terminal contact assembly rotatably mounted in said body, said terminal contact assembly comprising inner and outer terminal contact members concentrically arranged and electrically insulated from one another and said outer terminal contact member having a threaded external surface disposed in screw-threaded engagement with said internally threaded portion for adjusting the position of said terminal contact assembly in said body, a locking nut mounted on said outer terminal contact member for locking said assembly in an adjusted position, a movable contact member adapted to bridge said terminal contact members, said movable contact member comprising a flexible disc having a peripheral contact portion engaging said outer terminal contact member and a central contact portion adapted to make and break contact with said inner terminal contact member, a bi-metallic element mounted adjacent to said disc, and means for transmitting a force from the bi-metallic element to the disc, for urging said central contact portion of the disc into engagement with said inner terminal contact, the disc being resiliently biased in accordance with the adjustment of said terminal contact assembly to resist the force transmitted from the bi-metallic element.

9. A thermally operated switching device comprising a switch body, a sleeve member slidably mounted on said body, a pair of terminal contacts carried by said body, said contacts being concentrically arranged and electrically insulated from one another, a movable contact member adapted to bridge said contacts, said movable contact member comprising a flexible disc having a peripheral contact portion engaging the outer of said terminal contacts, a central contact portion adapted to make and break contact with the inner of said terminal contacts, and radially projecting portions arranged to be engaged by said sleeve member, a bi-metallic element mounted adjacent to said disc, and means for transmitting a force from the bi-metallic element to the disc for

urging said central contact portion into engagement with the inner of said terminal contacts, said disc being resiliently biased to resist the force transmitted from the bi-metallic element, and said sleeve member being movable into engagement with said radially projecting portions of the disc for flexing the disc against its bias for resetting the device.

10. A thermally operated cut-out switch for domestic electrical equipment, comprising a switch body, said switch body providing an internally threaded portion, a sleeve member slidably mounted on said body, a terminal contact assembly rotatably mounted in said body, said terminal contact assembly comprising inner and outer terminal contact members concentrically arranged and electrically insulated from one another and said outer terminal contact member having a threaded external surface disposed in screw-threaded engagement with said internally threaded portion for adjusting the position of said terminal contact assembly in said body, a locking nut mounted on said outer terminal contact member for locking said assembly in an adjusted position, a movable contact member adapted to bridge said terminal contact members, said movable contact member comprising a

flexible disc having a peripheral contact portion engaging said outer terminal contact member, a central contact portion adapted to make and break contact with said inner terminal contact member, and radially projecting portions arranged to be engaged by said sleeve member, a bi-metallic element mounted adjacent to said disc, and means for transmitting a force from the bi-metallic element to the disc for urging said central contact portion into engagement with said inner terminal contact member, said disc being resiliently biased in accordance with the adjustment of said terminal contact assembly to resist the force transmitted from the bi-metallic element, and said sleeve member being movable into engagement with said radially projecting portions of the disc for flexing the disc against its bias for resetting the switch.
